[57] CLAIM

The ornamental design for a printer housing or similar article, substantially as shown and described.

DESCRIPTION

FIG. 1 is a right front perspective view of a printer housing or similar article showing my new design; FIG. 2 is a left front perspective view taken at a slightly different angle;

FIG. 3 is a rear perspective view thereof; and
FIG. 4 is a right side elevational view thereof.

The side opposite is the same as the side shown; and
FIG. 5 is a front elevational view of the printer housing or similar article.
